SELECTOR SWITCH

Charles L. Howard, San Bruno, Calif.

Application March 9, 1940, Serial No. 323,147

1 Claim. (Cl. 200—6)

My invention relates to a switch for selectively closing electrical circuits, such as test circuits for radio tubes.

It is among the objects of my invention to provide a selector switch operated by a key.

Another object is to provide a key operated switch by which circuits are selectively established in accordance with characteristics of a particular key used to operate it.

A further object is to provide a key operated switch for radio test circuits, whereby circuits for different types of tubes may be established by merely using different keys for operating the switch.

A still further object is to provide an improved arrangement of contact arms and terminals on the switch.

The invention possesses other objects and features of advantage, some of which, with the foregoing, will be set forth in the following description of my invention. It is to be understood that I do not limit myself to this disclosure of species of my invention, as I may adopt variant embodiments thereof within the scope of the claim.

Referring to the drawing:

Figure 1 is a vertical sectional view of the switch with portions of the forward side plate shown in elevation to illustrate the key slot.

Figure 2 is an end elevational view of the switch; and

Figure 3 is a fragmentary horizontal sectional view showing the key in closed switch position.

Figure 4 is a detail elevational view showing a series of terminals and a pair of associated contact arms; and

Figure 5 is a plan view of the same.

Figure 6 is a detail sectional view showing the brush of a contact arm.

In terms of broad inclusion, the selector switch of my invention comprises a contact arm, and key operated means for moving the arm to a predetermined position. A plurality of such contact arms are preferably provided for selective engagement with a plurality of terminals to establish different circuits connected therewith. The operating means preferably comprises a key having a plurality of spaces engageable with the arms for moving the latter to predetermined positions upon turning the key. With this switch different groups of circuits, such as radio test circuits may be selectively closed depending upon the shape characteristics of different keys for operating the switch. Thus, one key may be designed for closing circuits to test one type of radio tube, and another key may be designed for

closing circuits to test another type of tube. It is understood that the suggested use of my switch for radio test circuits is merely for purposes of illustration, and that the device may be used wherever a selector switch is desired.

In greater detail, and referring to the drawing, my switch comprises a frame having side plates 2 and an inclined bottom plate 3. A plurality of contact arms 4 are pivotally mounted on the frame on a rod 6 extending transversely between the central portions of plates 2, thus mounting the arms for pivotal movement about a common axis. Collars 7 about rod 6 hold the arms properly spaced, and suitable springs 8 normally retain the arms in retracted position with the upper ends aligned. The lower ends of the arms are preferably bent to equally space the latter for registration with guide slot 9 in bottom plate 3, through which pointed ends 11 of the arms project. Abutment of arm ends 11 with the ends of the slot serves as limit stops for the arms in retracted position.

A plurality of series of terminals 12 are arranged in rows at the top of the frame. These terminals are fastened to arcuate insulating strips 13 held by cross rods 14 between side plates 2. In the structure shown, three rows of the terminals are illustrated with nine terminals in each row, but it is understood that both the number of rows and number of terminals therein may be varied, as may also be the number of contact arms 4, there being twice as many arms as rows of terminals. Each terminal is secured to its mounting strip 13 by a rivet 16 having a head to provide a contact on the side of the strip opposite the terminal as shown in Figure 6.

Along each side of strip 13 is mounted another insulating strip 17 spaced by collars 18 on rods 14. On each strip 17, facing the row of terminals, is a contact bar 19 secured by rivets 20. An end terminal 21 fastened by one of these rivets provides a circuit connection for the bar. A terminal unit as shown in Figure 5 is thus made up of a row or series of the terminals 12, and a pair of contact bars 19. There being three rows of terminals in the structure illustrated, there are three of these terminal units.

Means are provided on contact arms 4 for bridging a bar 19 with one of the associated terminals 12. For this purpose a brush 22 is mounted on the upper end of each arm, comprising a connected pair of flexible strips riveted to an insulating piece 23 secured to the arm. A pair of arms 4 is associated with a terminal unit with 55 a brush 22 interposed between each contact bar

19 and the row of terminals, one of the brushes engaging directly with a terminal and the other brush making contact with a terminal through its rivet 16. Thus, circuit leads connected to contact bars 19 through end terminals 21 may be selectively connected with other circuit leads secured to terminals 12, the particular circuits closed depending upon the position of arms 4.

Key operated means are provided for moving arms 4 to predetermined positions. As best shown in Figures 1, 2 and 3, a key having a handle 26 and a head 27 is provided for insertion through frame block 28 to an operating position adjacent arm 4. A rounded core portion 29 of the key seats in a hollow, slotted rotor 31 journaled in the frame plates to give support for the key when the latter is turned. Head 27 of the key is preferably a flat plate having offset spaces 32 cut as steps along the edge of the plate. These spaces register with arms 4, and, when the key is turned to the horizontal position shown in Figure 3, the arms are moved to varying extended positions depending upon the shape characteristics of the key.

In the extended position of arms 4, the brushes make contact with selected terminals to close predetermined circuits. For closing other circuits a different key may be used. For example, in connection with radio test circuits a different key would be provided for different types of tubes for establishing the necessary connection for a particular tube. This selector switch is thus a great

convenience for quickly closing predetermined circuits for the many different types of tubes now required to be tested.

I prefer to provide a key having a head plate extending in opposite direction, with differently arranged offset spaces 33 cut in the opposite edge. Thus, the arms are moved to predetermined position when the key is turned in one direction, and are moved to other positions when the key is turned in the opposite direction. Spaces 33 of the key may be designed for establishing connection to test for shorts. Keys with three operating plates could be provided.

While I have described my device as a switch, it is understood that the key operated mechanism may be designed as a rheostat, in which case arms 4 would function as contact arms for resistance elements.

I claim:

A selector switch comprising a plurality of series of terminals, a plurality of contact arms each selectively engageable with the terminals of a series, and a key having oppositely disposed faces for engaging the arms when the key is turned in either direction, one of said faces being shaped to move the arms into engagement with a selected combination of terminals when the key is turned in one direction and the other face being shaped to move the arms into engagement with another combination of terminals when the key is turned in the opposite direction.

CHARLES L. HOWARD.
